UNITED STATES PATENT OFFICE.

EDMUND F. JANTZ, OF CHICAGO, ILLINOIS.

COLLAR WRAPPER.

Application filed June 6, 1921. Serial No. 475,195.

To all whom it may concern:

Be it known that I, EDMUND F. JANTZ, a citizen of the United States, and a resident of the city of Chicago, in the county of Cook and State of Illinois, have invented certain new and useful Improvements in a Collar Wrapper; and I do hereby declare that the following is a full, clear, and exact description of the same, reference being had to the accompanying drawings, and to the numerals of reference marked thereon, which form a part of this specification.

This invention relates to special packages of the sort used to deliver merchandise and is particularly adapted for holding a few collars.

It is an object of this invention to provide a wrapper into which the collars may be easily and quickly inserted and which can be closed about the collars with the least expenditure of time and effort.

It is a further object of this invention to provide a wrapper which before it is applied to the collars can be kept in a substantially flat form.

It is a further object of this invention to construct such a wrapper of a sheet material of an inexpensive kind.

Other and further important objects of the invention will be apparent from the disclosures in the specification and the accompanying drawings.

The invention (in a preferred form) is shown in the drawings and hereinafter more fully described.

On the drawings:

Figure 1 is a plan view of the wrapper in its flat condition.

Figure 2 is an end view of the wrapper with the collars contained therein.

Figure 3 is a central section of Figure 2.

Figure 4 is a radial section of Figure 2 with the end portions of the wrapper turned into final position.

As shown on the drawings:

The wrapper comprises a sheet 1 of relatively stiff material such as cardboard or pasteboard, or even heavy manila paper. This sheet forms an oblong having near each end a slot 2 at right angles to the long di-

mension of the oblong. These slots enter from opposite edges and form tongues or tabs 3. Secured to each long edge of the sheet 1 is a rectangle of more flexible material such as tissue paper or thin wrapping paper forming a pair of end closures 4 and 5.

In using the device the two end portions 3 are brought around and caused to interlock with one another by means of the slits 2, as shown at 6 in Figures 2 and 3, forming a cylindrical shell. The collars or other articles to be contained within the package are then put into the cylindrical shell, as illustrated in Figure 2. In the case of collars it is done by rolling the collars together until they are of sufficiently small diameter to be contained within the shell, the ends of the collars overlapping, as shown at 7. Preferably the width of the oblong 1 is sufficient to more than extend from the bottom 8 to the top 7 of a standard collar as is illustrated in Figure 4. When the collars have been placed within the receptacle the flexible portions 4 and 5 are tucked in at each end 75 until they form an inner covering for the collars as shown in Figure 4. The package is then ready to deliver to the customer and need not be tied by a string or secured in any further manner.

I am aware that changes in construction may be made and materials varied without departing from the principles of this invention, and I do not purpose therefore limiting the patent granted otherwise than necessitated by the prior art.

I claim as my invention:

1. In a collar container, a strip of stiff wrapping material having slots near each end thereof at right angles to the length of 90 said strip whereby said ends may be secured together, and wings of flexible wrapping material attached to the long edges of said strip and stopping at said slots, the width of said strip being greater than the height 95 of a standard collar and the length being less than the circumference of such a collar.

2. In a collar container, a strip of stiff wrapping material having slots near each end thereof at right angles to the length of 100

said strip whereby said ends may be secured together, and wings of flexible wrapping material attached to the long edge of said strip and stopping at said slots, the width of 5 said wings being sufficient to allow them to overlap against the inside surface of the collars when tucked into the central part of the package.

In testimony whereof I have hereunto subscribed my name in the presence of two 10 subscribing witnesses.

EDMUND F. JANTZ.
